UNITED STATES PATENT OFFICE.

HAROLD D. MORTON, OF MITCHELL, NEBRASKA.

POISON-LABEL.

1,221,572.

Specification of Letters Patent. Patented Apr. 3, 1917.

Application filed June 13, 1916. Serial No. 103,423.

To all whom it may concern:

Be it known that I, HAROLD D. MORTON, a citizen of the United States, residing at Mitchell, in the county of Scotts Bluff and 5 State of Nebraska, have invented certain useful Improvements in Poison-Labels, of which the following is a specification, reference being had therein to the accompanying drawing.

10 This invention relates to improvements in poison labels for attachment to bottles, one object of the invention being the provision of a label which will be illuminated at all times so as to indicate in the dark the 15 presence of such bottle.

A further object of this invention is the provision of a label of this character which carries thereon a small flask which contains equal parts of phosphorus and olive oil, so 20 that the phosphorescence will be visible at all times and indicate at a glance when such label is applied to a bottle that the bottle contains a poison.

In the accompanying drawings:

25 Fig. 1 is a front elevation of the bottle with the present label applied.

Fig. 2 is a section taken on line 2—2 of Fig. 1.

30 Fig. 3 is a plan view of the fluid containing bottle or vial with the label.

Fig. 4 is a sectional view through the pocket for carrying the vial.

Referring to the drawings, the numeral 5 designates a small bottle or vial having a 35 stopper 6 and containing in the space 7 equal parts of phosphorus and olive oil, the upper space 8 being illuminated by the phosphorus, so that when the vial is snugly fitted

and frictionally engaged within the elastic opaque pocket 9, the cut away portions or 40 stenciled front face 10 thereof will permit of the phosphorus to be visible therethrough so that the same will be clearly visible in the pocket and indicate that the bottle 11, which has the elastic band 12 45 carrying the pocket placed thereupon, contains poison. Because of the frictional relation of the pocket and vial, the latter is retained against accidental displacement from the pocket. 50

Should the phosphorus at any time become dim, it is simply necessary to remove the stopper from the vial and permit the entrance thereto of the atmosphere which sets up oxidation sufficiently to renew the 55 phosphorescence. The pocket for containing the vial may be made of any desired elastic material, preferably rubber or rubber compound.

From the foregoing description, it is evident that the present label may be readily attached upon bottles of any character that may contain poison, and that due to the phosphorescence, the usual skull and crossbones to indicate poison which are stenciled 65 in the front face of the pocket will be visible in the dark.

What I claim as new is:—

A label for bottles, including a stenciled opaque and elastic pocket removably mounted on the bottle, and a transparent phosphorus containing vial removably and frictionally engaged in the pocket so as to be retained against accidental displacement. 70

In testimony whereof I affix my signature. 75

HAROLD D. MORTON.
